Patented Mar. 1, 1921.

FIG. 1.

FIG. 2.

INVENTOR:
W. K. Mason
by Knight Brown Quincy May
ATT'YS

UNITED STATES PATENT OFFICE.

WILLIAM K. MASON, OF CAMBRIDGE, MASSACHUSETTS.

HEATER FOR GARAGES, &c.

1,370,471.

Specification of Letters Patent.

Patented Mar. 1, 1921.

Application filed August 9, 1920. Serial No. 402,142.

To all whom it may concern:

Be it known that I, WILLIAM K. MASON, a citizen of the United States, residing at Cambridge, in the county of Middlesex and 5 State of Massachusetts, have invented new and useful Improvements in Heaters for Garages, &c., of which the following is a specification.

This invention relates to a fluid heating and 10 circulating system adapted for use in heating garages, and including a burner and a boiler operatively associated with the burner, so that its contents will be heated by the latter, the boiler constituting a conduit member, a radiator, and flow and return conduit members, constituting, with the boiler and radiator, a fluid-circulating system, the arrangement being such that fluid heated in 15 the boiler is circulated through the radiator, so that heat is radiated by the latter.

The invention has for its object to provide for a heating system of this character, a vapor proof protecting box adapted to prevent liability of the explosion of combustible 20 vapors present in garages.

The invention is embodied in the improvements which I will now proceed to describe and claim.

Of the accompanying drawings forming 30 a part of this specification,—

Figure 1 shows, partly in elevation and partly in section, a fluid heating and circulating system embodying the invention and in section a protecting box associated with 35 the system.

Fig. 2 is a partial end elevation and a section on line 2—2 of Fig. 1.

The same reference characters indicate the same parts in all of the figures.

40 In the drawings, 12 represents a burner, which as here shown is constructed to burn gas, the burner being elongated and provided with a plurality of gas outlets 13. I hereinafter refer to the burner 12 as the 45 main burner, to distinguish it from the pilot burner hereinafter described.

14 represents a boiler, which is operatively associated with the burner 12 by being so located that fluid in the boiler may be 50 heated by the burner, the boiler constituting a conduit member. 15 represents a radiator, which may be of any suitable form. 16 represents a flow conduit member connecting the boiler with one portion of the radiator. 55 17 represents a return conduit member,

connecting another portion of the radiator with the opposite end of the boiler.

The boiler, the radiator, and the flow and return conduit members constitute a fluid-circulating system, in which the circulation 60 may be as indicated by arrows on the drawing.

18 represents a pilot burner, which as here shown, is a gas burner, and is arranged to ignite gas issuing from the burner outlets 65 13.

19 represents a vapor-proof box inclosing the burners 12 and 18, and the boiler 14. The radiator is external to the box 19, and the flow and return conduit members 16 and 70 17, extend from within the box to the radiator through orifices 21, closely fitting the said conduit members.

An ignition system operable from the exterior of the box 19 is shown somewhat diagrammatically by the drawing, said system including conducting wires 22, forming a spark gap at 23 and a suitable source of electricity in a casing 24 at the outside of the box 19, a suitable switch 25 being provided 80 to make and break an electric circuit through the wires 22.

The box 19 has an air-admitting opening or openings at 26. Between said opening and the portion of the box containing the 85 burners and boiler I interpose suitable means permitting air to enter the box, and preventing the explosion of combustible vapor exterior to the box, said means being here shown as embodied in two partitions 90 27, of wire gauze, or finely perforated sheet metal.

The box is provided with means for conducting products of combustion therefrom, to a point remote from the box, and preferably outside of the building in which the heater is located, said means being preferably embodied in a pipe or conduit 28, communicating with an opening in the upper portion of the box. Said conduit is sufficiently elongated to prevent contact between hot products of combustion conducted thereby, and combustible gases surrounding the box.

Although the burners may be adapted for 105 use with any suitable fuel, such as petroleum, I prefer to employ gas burners, as above stated.

When gas is used for the fuel, I provide 110 gas-supplying means, including a casing 29,

external to the box 19, and provided with an outer nipple 30, and with an inner nipple 31, said nipples closely fitting orifices 32 in the box. The inner nipple 31 communicates with 5 the main burner 12, and the outer nipple 30 communicates with the pilot burner 18.

The casing 29 is provided between the nipples 30 and 31 with an inner burner cock 33, controlling the supply of gas to the main 10 burner 12. The casing is also provided between the nipple 30 and the gas inlet 34, with an outer cock 35, controlling the supply of gas to both burners.

To regulate the supply of gas through 15 the burners, I provide needle valves 36, adapted to coöperate with tapering valve seats 37 in the nipples 30 and 31.

The box 19 is provided, in addition to the 20 openings 32, receiving the gas-conducting nipples or branches 30 and 31, and the openings 21, through which the conduits 16 and 17 pass, with an opening at 33, through which pass the wires 22 forming elements of the ignition system. Said openings are 25 formed to have a vapor-tight fit around the conduits 16 and 17, the branches 30 and 31, and the conducting wires 22, so that combustible vapor cannot pass through the openings, the box provided with said openings 30 and with the foraminous partitions 27 being, therefore, vapor-proof. If desired, the said openings may be provided with packings of refractory material.

It will now be seen that my invention is 35 embodied in a vapor proof protecting box associated with a fluid heating and circulating system which includes a burner, a boiler arranged to be heated by the burner, a radiator, and flow and return connections connecting the boiler with the radiator, the said 40 vapor-proof box inclosing the burner and the boiler, but not the radiator, so that the latter is exposed to radiate heat outside the box, one wall of the box being interposed 45 between the boiler and the radiator and the entire box being outside the radiator.

I call the part 14 a boiler for the sake of convenience, and without intending to imply that water is necessarily boiled therein. 50 When the fluid-circulating system is entirely filled with water, no boiling takes place in the part called the boiler.

The radiator is supported by legs 37 at 55 opposite sides of the box. The legs at one end may be longer than those at the opposite end to incline the radiator from end to end, and thus accelerated circulation.

A cup 38 for the introduction of water into the boiler may be provided at any suitable 60 part of the circulating system, said cup having a cock 39.

In Fig. 1 I show packing means surrounding the box openings 21, and the conduits 16 and 17, said means being embodied in metal glands 40 attached by screws to the ends of

the box, and compressible gaskets or packing-rings 41, preferably of asbestos, compressed by said glands against the conduits and forming vapor-proof joints. Similar packing means may be provided at the openings 32, although not necessary at these openings, because the nipples 31 and 32 have shoulders bearing tightly on outer surfaces of the box. The fluid-heating and circulating system is self-contained, and partly 70 inclosed in the vapor-proof box, so that the fluid circulates in a path which is partly within and partly without the box.

The glands 40 and the packings 41 constitute an element of safety means associated with the conduit openings 21. The partitions 27 constitute an element of safety means associated with the air-admitting opening. The conduit 28 constitutes an element of safety means associated with the 80 opening for the escape of the products of combustion. Each of said elements is adapted to prevent the explosion, by the burner, of gases outside the box and in the immediate vicinity of the conduits, the air inlet, and 85 the products outlet. The box equipped with said safety elements enables the burner to be safely used to heat the boiler and the radiator in a garage where explosive vapor is liable to be mixed with and carried by 90 the air.

It will be seen that the boiler and the burner are inclosed by a box-like structure forming a chamber inclosing the boiler and the burner. Said chamber includes air-admitting and flame-confining portions formed by the foraminous partition or partitions 27. The major portion of the chamber constitutes an impervious portion, in the sense that, unlike the portion 27, it is made 100 of material impervious to air. The air-admitting portion 27 is marginally connected with the impervious portion by means forming flame-tight joints, said means being shown as embodied in flanges 105 45, fixed to the impervious portion and having wide bearing surfaces contacting with correspondingly wide surface areas of the portion 27. The area of the said contacting surfaces is such that they form flame-tight joints, that is to say, joints through which flame cannot pass from the interior 110 of the box. I find that flame will not shoot through a crevice of considerable width between two contacting surfaces.

The openings 21 occupied by the conduits 16 and 17, and the opening for the escape of products of combustion, are formed in the impervious portion of the chamber, which is provided, as shown, with means 115 120 for forming flame-tight joints around said conduits, and with a safety conduit 28 for preventing explosion, by the burner, of gases in the vicinity of the escaping products.

The impervious portion of the chamber 130

is of sectional construction, that is to say, it includes a section formed by the upright walls of the box-like structure and a section formed by a top 19^a, which is a separate piece. Said sections are marginally connected with each other by means forming flame-tight joints, said means being shown as embodied in flanges 46, fixed to one of the sections, and having wide bearing surfaces contacting with, and suitably secured to, correspondingly wide surface portions of the other section.

It is evident from the foregoing that I have provided against the possible explosion of gases or vapors contacting with any portion of the exterior of the box or box-like structure.

I claim:

1. A garage heater comprising a radiator, a boiler located under and spaced from the radiator, flow and return conduits connecting the radiator with the boiler, a burner arranged to heat the boiler, and a box-like structure located below the radiator and forming a chamber inclosing the boiler and the burner, said chamber including an impervious portion composed of sections marginally connected with each other by means forming flame-tight joints, and a 30 foraminous flame-confining and air-admit-

ting portion marginally connected with the impervious portion by means forming flame-tight joints, the said impervious portion being provided with an elongated conduit for the escape of products of combustion, openings occupied by said flow and return conduits, and means forming flame-tight joints around said conduits.

2. A garage heater comprising a radiator, a boiler located under and spaced from the radiator, flow and return conduits connecting the radiator with the boiler, a burner arranged to heat the boiler, and a boiler and burner-inclosing box located below the radiator, and having an opening for the admission of air, an opening for the escape of products of combustion, openings occupied by said flow and return conduits, and elements of safety means associated with said openings for preventing the explosion, by the burner, of gases at the exterior of the box, the safety means elements associated with the conduit openings being embodied in compressible gaskets surrounding the conduits, and glands secured to the 50 box and compressing said gaskets to form vapor-proof joints.

In testimony whereof I have affixed my signature.

WILLIAM K. MASON.
